UNITED STATES PATENT OFFICE.

JAMES M. MONTGOMERY, JR., OF COLUMBUS, OHIO.

FOLDING BEDSTEAD.

SPECIFICATION forming part of Letters Patent No. 276,859, dated May 1, 1883.

Application filed March 23, 1883. (No model.)

To all whom it may concern:

Be it known that I, JAMES M. MONTGOMERY, Jr., of Columbus, in the county of Franklin and State of Ohio, have invented certain new and useful Improvements in Folding Bedsteads; and I do hereby declare that the following is a full, clear, and exact description of the invention, which will enable others skilled in the art to which it appertains to make and use the same, reference being had to the accompanying drawings, which form a part of this specification, and in which—

Figure 1 is a perspective view of my improved folding bedstead closed. Fig. 2 is a vertical section of the same. Fig. 3 is a similar view of the bedstead opened, and Figs. 4, 5, and 6 are perspective detail views.

Similar letters of reference indicate corresponding parts in all the figures.

20 My invention has relation to folding bedsteads; and it consists in the improved construction and combination of parts of a bedstead in which the bed-frame may be folded into a casing and covered by a curtain, causing it to resemble a book-case or similar article of furniture, while the bottom of the bed-frame may be open, allowing perfect and free ventilation in the bed, as hereinafter more fully described and claimed.

30 In the accompanying drawings, the letter A indicates a casing, consisting of a back piece, B, which, in connection with the side pieces C, support a top piece, D, which may be ornamented in any desired manner to resemble the top of whatever article of furniture the bedstead is intended to resemble, while the side pieces likewise may be paneled and ornamented in any desired manner.

The lower portions E of the side pieces are 40 wider up to the height to which it is desired to have the bed hinged than the upper portions, and are connected at their front edges by a board or front piece, F, preferably ornamented to resemble the front of one or more drawers, upon the upper edge of which is hinged a board, G, which may be swung obliquely inward when the bed is closed, securing the lower end of the curtain H, the roller I of which is journaled in the forward portion 45 of the top piece, and covering the swinging support of the bed-frame.

The bed-frame consists of a rectangular

frame, J, the foot board K of which is turned slightly inward at its lower portion to allow free space for the curtain-roller and curtain. 55

Two transverse boards, L and M—one at the foot end and one at the head end of the bed—serve as supports for a bed-bottom, and a board, N, having legs O at its lower edge, is hinged to the board L at the foot end, swinging down 60 when the bed is lowered, supporting that end, while they will depend flat against the bottom of the bed when it is raised.

A board, P, is hinged at the bottom of the casing, near the front, upon two trunnions, Q, 65 projecting laterally from the lower corners of the board upon which they are fastened, and resting in bearings R in the bottom of the casing, as shown in detail in Figs. 4 and 5, and the ends of the board rest, when the bed is 70 folded down, upon the inclined edges of two supports, S, fastened upon the side pieces.

Two upward and slightly rearwardly projecting castings or arms, T, forming a recess, U, at their lower ends, which clasps the upper 75 edge of the swinging board, are fastened upon the same, and their upper rounded ends V fit into correspondingly-shaped recesses, W, formed by the curved inwardly-projecting flanges X of two castings Y, which are fastened upon 80 the side rails of the bed-frame, and to a cross-piece, Z, in the bottom of the same. The two sides of these recesses correspond in shape to the two sides of the arms T in such a manner that the inner side of the upper or outer portion of the flange bears against the outer side of arm T when the bed is folded down, while when the bed is closed the inner portion of the flange bears against the inner side of the arm, thus presenting a larger bearing-surface 85 when the bed is in its two positions.

Two cross-supports, a, are secured to the inner sides of the side pieces at the height of the upper edge of the bed-frame, and serve to prevent the latter from being tilted too far 95 down, the upper edges of the frame near the head end bearing against them, and two guides, b, having curved edges, and fastened in the lower rear corner of the frame, serve to guide the head end of the bed into position when 100 the bed is folded.

It will be seen that, by hinging the bed-frame in this manner upon a swinging board and upon the upward and rearwardly project-

ing arms by the flanged castings, I divide the weight of the bed over the arms, the swinging board, and the inclined supports S, when the bed is folded down, while when the bed is folded up in the casing the head end will rest upon the bottom of the casing, while the swinging board will stand in a vertical position, holding the bed into the casing by its rearward-projecting arms.

10. When the bed is folded up the curtain is drawn down, covering the front, and held down by the inclined board G, which is swung up in position, as shown in Figs. 1 and 2, covering the swinging board and that portion of the bed from view.

Having thus described my invention, I claim and desire to secure by Letters Patent of the United States—

1. In a folding bedstead, the combination 20 of the bed, having castings Y secured upon the side rails and having inwardly-projecting curved flanges X, with the swinging supporting-board P, having upward and rearwardly projecting arms T, projecting into the recesses 25 formed by flanges X, said board being hinged in the bottom of the upright casing of the bedstead, as and for the purpose shown and set forth.

2. In a folding bedstead, the combination 30 of the bed-frame, having castings Y, forming curved flanges X, swinging board P, having

upward and rearwardly projecting arms T at its upper corners, and trunnions Q, fastened at its lower corners, and bearings R, fastened at the bottom of the casing, as and for the purpose shown and set forth. 35

3. The herein-described folding bed, consisting of the frame A, hinged board G, bed-frame J, hinged legs N O, flanged castings Y, arms T, swinging board P, trunnions Q, bearings R, cross-supports a, guides b, and curtain H I, all constructed, combined, and arranged as and for the purpose shown and set forth. 40

4. A folding bedstead, open at the front for the reception of the swinging bed-frame, and 45 having a rolling curtain journaled in the forward portion of the top piece, as and for the purpose shown and set forth.

5. The folding bedstead consisting of the casing A, open at the front, and having a roller, 50 I, provided with a curtain, H, journaled in the forward portion of the top piece D, and swinging bed-frame J, as and for the purpose shown and set forth.

In testimony that I claim the foregoing as 55 my own I have hereunto affixed my signature in presence of two witnesses.

JAMES M. MONTGOMERY, JR.
